UNITED STATES PATENT OFFICE

GEORGE WASHINGTON BLEDSOE, WILLIAM S. LLOYD, AND CARL DON YENCER, OF
EL PASO, TEXAS

PUMP

Application filed January 9, 1930. Serial No. 419,632.

This invention relates to a simple cylinder pump to be used in connection with pumping of water or other liquids, to be used and set underground and under the liquid in the well.

5 An object of the invention is to provide for utilizing the weight of the sucker rod falling back into the cylinder to force the liquid out the same as the other stroke, and to furthermore provide a pump that will not lock with 10 sand because the sand will travel through the outlet pipe before it will cause the locking of the parts.

Further objects of the invention are to provide, in a manner as hereinafter set forth, a 15 device of the character referred to, that is strong, compact and durable, very simple in its method of assembly, thoroughly reliable for its intended purpose, requiring very little effort to use the same, that may be operated by hand or a prime mover, that is comparatively inexpensive to manufacture and operate.

With the foregoing and other objects in view, the invention consists of a careful construction, combination and arrangement of parts, as will be hereinafter more specifically described and illustrated in the accompanying drawings, wherein is disclosed an embodiment of the invention, but it is to be understood that changes, variations and modifications, may be resorted to without departing from the spirit of the claim hereto appended.

In the drawings wherein like reference 35 characters indicate corresponding parts throughout the several views:—

Figure 1 is a side elevation of the pump in accordance with the present invention,

Fig. 2 is a vertical section in detail, thereof, 40 Fig. 3 is a horizontal section taken substantially on the line 3—3 of Fig. 1 and looking in the direction of the arrow.

Referring to the drawings in detail, 5 indicates generally, a segmental shaped casing or union formed with an interior U-shaped 45 passage 8. The segmental casing forms a base that is adapted to be vertically supported below the level of the liquid in the well on a tubular support 6, the bottom of which rests upon the floor of the well.

The upper end of the support 6 is peripherally threaded to receive a depending, circumferentially threaded boss 7 that depends from the lower end of the base 5.

The top or chorded face of the base 5 is 55 formed with two peripherally threaded openings, 9 and 10 and the opening 9 communicates with one leg 11 while the opening 10 communicates with the other leg 12 of the U-shaped passage 8. Where the leg 12 of the 60 passage merges with the peripherally threaded opening, the walls about the passage are formed with a valve seat 13, upon which rests a ball check valve 14.

The lower end of a cylinder 15 is thread- 65 edly connected to the opening 9 and supported vertically by the casing or base 9. A conductor pipe 16 of materially less diameter than the cylinder is threadably connected at its lower end to the peripherally threaded 70 opening end and is supported on the base 5. The lower end of the cylinder 15 communicates with the legs 11 and passage 8, while the lower end of the conductor 15 communicates 75 with the leg 12 of the passage.

The conductor 15 extends to the top of the well and forms the outlet of the pump. Spaced above the valve seat 13, are a pair of radially disposed crossed bars 17, 18, the ends of which are anchored to the walls of the 80 conductor pipe 16, and these bars form a limit stop for the upward movement of the ball check valve 14.

The cylinder 15 should be such length that it extends above the highest level of the liquid 85 in the bottom of the well and it is formed with a plurality of radial openings 19 above the highest point in the stroke of the piston to be presently described.

A hollow piston 20 is slidably mounted for vertical reciprocation in the cylinder 15, and is formed with a plurality of vertically spaced grooves 21 about its periphery, in which are seated leather gasket rings 22. 90 The piston 20 is formed with a solid cap 23 in which there is counter-sunk a peripherally threaded socket 24 to receive the lower end of the operating or sucker rod 25 that extends through the top of the ground, and 100

may be connected to a hand pump or other operating means.

The top 23 is inset with respect to the side walls of the piston, and on the tapered shoulder 26, there are formed a plurality of radially inclining openings 27 that form a communication between the walls of the cylinder and the hollow interior 28 of the pistons.

The bottom of the piston is formed with an upstanding hollow, spider 29 formed with a substantially frusto-conical shaped, vertically disposed passage 30. The spider 29 is formed with a plurality of radially inclined openings 31 that form a communication with the hollow interior 28 and the passage 30.

A valve stem 32 extends through the passage 30 and is peripherally threaded as at 33 on its upper end, so that it extends into the hollow interior 28 of the piston. Threadably engaged on the projecting end 33 are a pair of nuts 34 that are adapted to rest upon the upper face of the spider 29, and form a water-tight connection with respect to the passage 30.

25 The valve stem 32 is applied through the passage 30 and a valve 35 having a beveled peripheral edge is adapted to seat in the frustum portion of the passage 30 and on the down stroke of the piston.

30 In the operation of the pump, water or other liquids will enter the cylinder 15 through the openings 19. On the upstroke of the piston 20 the water finds its way to passage 27, hollow interior 28, then through 35 openings 31, since the valve 35 will be opened on the upstroke.

The water then collects in the passage 8 of the base 5. At the end of the stroke of the piston 20, which is below the openings 19 40 in the cylinder, the check valve 35 closes on the downward stroke, whereupon the base of the piston 20 acts as a plunger for the water through the leg 12 of the base, and into the conductor pipe 16 through the surface of the 45 earth.

It requires very little energy on the part of the operator on the downstroke of the piston, since the weight on the rod 25 will almost be sufficient to force the water through the 50 conductor 15.

From the drawings, it will be evident that the passage 8 diminishes in area from opening 6 to the openings 10.

It is to be understood that by describing 55 in detail herein any particular form of the invention, structure, or arrangement, it is not intended to limit the invention beyond the terms of the claim, or the requirements of the prior art.

60 Having thus described our invention, what we claim as new is:—

A pump of the character described comprising an elongated, vertically disposed casing, a hollow piston mounted for reciproca- 65 tion in the casing, an integral tapered pro-

jection extending upwardly in the piston from the lower end thereof and terminating in a flat upper end, the upper end portion of the projection having a centrally disposed opening extending therethrough, said projection providing a substantially conical recess in the lower portion of the piston, the recess constituting a valve seat, the projection being still further provided with a plurality of circumferentially spaced passages in intermediate portions establishing communication between the conical recess and the interior of the piston, a reciprocating check valve engageable on the seat to control the passage of fluid from the casing into the piston through the recess and passages, a threaded stem on the valve extending slidably through the opening in the projection, a nut threaded for adjustment on the stem and engageable on the upper end of the projection for limiting the opening movement of the valve, the piston being provided with fluid outlet openings in its upper portion.

In testimony whereof we affix our signatures.

GEORGE WASHINGTON BLEDSOE.
